KARL ERNST WENZEL, OF HAMBORN, GERMANY, ASSIGNOR TO RANGIERTECHNISCHE GESELLSCHAFT M. B. H., OF HAMBORN, GERMANY, A CORPORATION OF GERMANY.

SAFETY CONTRIVANCE ON PERMANENT RAILWAY TRACKS.

Application filed January 6, 1928, Serial No. 244,972, and in Germany March 21, 1927.

This invention relates to an improved device for a reliable operation of safety-contrivances on a permanent railway track with the air of an insulated rail section of known art, 5 and it consists in the combination of a two-part insulated rail section and a relay comprising an armature and two windings, or instead of the latter one winding only and two series resistances connected in parallel there- 10 to, the two parts of said insulated rail section being connected each to one of said windings, or to one of said series resistances—as the case may be, and adapted to be simultaneously short-circuited for an attraction of the 15 relay armature by each two succeeding train wheel axles running over the same, while one of said windings, or one of said series resistances—as the case may be, when current-fed holds the attracted armature in said latter 20 position upon the short-circuit of one part only of said insulated rail section.

The accompanying drawing illustrates diagrammatically by way of example in Figs. 1 and 2 two preferred constructional 25 forms of the improved device, each in a plan view.

Referring to Fig. 1: The two insulated rail sections i^1 and i^2 are connected each with a relay winding r^1 and r^2 respectively, which windings are so determined that with a train wheel axle running over one of the insulated rail sections only an attraction of the relay armature r does not take place, said attraction being effected only when the insulated 30 rail sections i^1 and i^2 are simultaneously short-circuited by means of two succeeding train wheel axles running over the same (as will be clear from Fig. 2). On the other hand, one current-fed winding only is capable of holding the attracted armature in 35 said latter position upon the short-circuit of one part only of said insulated rail section. Thus, the relay armature is not attracted when the train wheel axle runs over the first

section i^1 of the insulated rail only and thus 45 an interruption of the short-circuit by any insulating dirt layer on said rail cannot become effective in a detrimental way. The relay is, as mentioned, attracted only after the two insulated rail sections i^1 and i^2 are simultaneously short-circuited. A subsequent interruption of the short-circuit remains ineffective, and a dropping of the relay armature r does not take place until the last train wheel 50 axle has left the rail section i^2 . 55

Referring to Fig. 2: The same effect is attained by means of an ordinary relay r^3 , which is connected in parallel to two series resistances w^1 and w^2 , that are connected to the insulated rail sections i^1 and i^2 respectively. Thereby, the current reception by the relay is so throttled that it acts in a similar manner to that of the relay with a double winding illustrated in Fig. 1. 60

To further increase the safety of working 65 so that also on the second section i^2 a false operation of the relay is impossible, a further protective insulated section with a third resistance may be arranged in advance of the section i^2 . 70

What I claim is:—

In combination, a relay comprising a winding and an armature, two series resistances connected in parallel to said relay, and a two-part insulated rail section of a permanent railway track, the two parts of the insulated rail section being connected each to one of said series resistances and adapted to be simultaneously short-circuited for an attraction of the relay armature by each two succeeding train wheel axles running over the same, one of said resistances when current-fed holding the attracted relay armature in 75 said latter position upon the short-circuiting of one part only of said insulated rail section. 80 85

In testimony whereof I have hereunto set my hand.

KARL ERNST WENZEL.
